DESIGN FOR A GIRDLE

Sigmund W. Kunstadter, Chicago, Ill., assignor to The Formfit Company, Chicago, Ill., a corporation of Illinois

Application January 18, 1939, Serial No. 82,414

Term of patent 7 years

To all whom it may concern:

Be it known that I, Sigmund W. Kunstadter, a citizen of the United States, residing at Chicago, Cook County, Illinois, have invented a new, original, and ornamental Design for a Girdle, of which the following is a specification, reference being had to the accompanying drawing, forming a part thereof, and in which

Fig. 1 is a front view of a girdle showing my new design; and

Fig. 2 a rear view thereof.

I claim:

The ornamental design for a girdle, as shown.
